Hanson & Hanson

Patented Nov. 23, 1926.

UNITED STATES PATENT OFFICE.

FRANK H. CHASE, OF PHILADELPHIA, PENNSYLVANIA; PHILIP R. CHASE EXECUTOR
OF SAID FRANK H. CHASE, DECEASED.

COMBINED HEEL AND ARCH SUPPORT.

Application filed October 10, 1922. Serial No. 593,547.

My invention relates to footwear, my purpose being to provide a combined heel and arch support for sustaining the arch of the wearer's foot and cushioning his heel. I aim to afford scientifically correct support for the foot under all conditions,—whether the arches are fallen or not,—while preferably permitting free movement of the foot; to preserve the original curvature of the shank of the shoe, and thus keep the shoe in proper shape; and to obviate risk of tripping from catching of the arch support on inequalities of the walking surface. The embodiment of my invention herein described comprises a relatively soft, pliable unitary device that correctly supports the arch directly from the ground, and continues to do so as the device wears down in service, and is characterized by the full universal flexibility and elasticity of one single piece of rubber.

The invention also relates to certain details, which will be fully described hereinafter.

25 In the accompanying drawings:

Fig. 1 is a perspective view of my improved combined heel and arch support.

Fig. 2 is an inverted perspective view of the same.

30 Fig. 3 is a side view.

Fig. 4 is a longitudinal sectional view.

Fig. 5 is a transverse sectional view on the line 5—5, Fig. 4.

35 Fig. 6 is a side view showing the heel and arch support attached to a shoe.

Fig. 7 is an inverted plan view of the heel and arch support attached to a shoe as illustrated in Fig. 6; and

40 Fig. 8 is a side view showing a modification in which the support is of a greater depth than the heel so that the device can be applied to the heel of a shoe which is partly worn.

45 Referring to the drawings, 1 is a shoe having a sole 2. 3 is the shank of the shoe, which is curved as illustrated in Fig. 6. 4 represents my combined heel and arch support, which, in the present instance, is made

of rubber, or a rubber composition, so that it is flexible and yields when pressure is applied to the shoe to which it is attached. The heel portion 5 is shaped, as clearly shown in the drawings, to conform to the shape of the finished heel of a shoe and has a central recess 6 of any shape desired. 55 The edges 7 of the heel are slightly raised so that, when the heel is secured to a shoe, the edges will fit snugly against the outer sole thereof. Projecting from the forward end of the heel section is the arch support 60 section 8 having the peculiar curve illustrated in Figs. 1 and 2, so that it will support the arch properly.

9 is the inside edge of a shoe. It will be noticed that the arch support 8 is close to 65 this edge. The general location of the arch support 8 transversely of the shoe sole 2 and of the heel 5 is also to be noted: i. e., that its center line lies to the inner side of the center of the heel 5 adjacent the latter, 70 and turns inward more and more toward the inner edge 9. Accordingly, the support 8 lies under the "inner aspect" of the foot as defined by the astragalus, scaphoid, and internal cuneiform bones, with its forward end 13 behind the forward "anchor" of 75 the longitudinal arch formed by the anterior head of the first metatarsal bone. This relation results from its own unconstrained configuration as molded,—as will be seen by 80 comparison of Figs. 1 and 2 with Fig. 7. Like those of the heel 5, the edges 10 of the arch support are raised so that, when the support 8 is secured to the shank of a shoe, the edges will fit snugly against the 85 shank. The sides 11 of the arch support are in the form of an O. G. curve. This gives a neat appearance to the arch support 8 and carries the supporting tread surface 12 a distance away from the edge of the shoe; also, the support 8 has a base much broader than its tread 12 for attachment to the shoe sole 2 and for receiving the weight 90 from the sole 2, so as to minimize spreading of the support and to obviate any possibility of torsional or transverse distortion. 95

When, therefore, pressure is applied to the tread surface 12 in walking, the arch support 8 is able to carry the weight firmly.

From Figs. 3 and 4 it will be seen that as the device 4 is molded the upper surface or edge of the support 8 is substantially in the same plane as that of the heel 5 (as indicated by the straight line α), with the support tip or end slightly raised above such plane at 13. In applying the heel and arch support to a shoe, the support 8 is bent or resiliently flexed downward from the straight line α so that its upper surface is curved to conform to the curve of the shoe shank 3 and its tread 12 is on a line with the tread of the ball and heel of the shoe,—even when off the ground.

Such resilient flexure of the support 8 in accommodating the device 4 to a shoe causes the support to press upward and fit closely against, or "hug" the shoe shank 3, and thus obviates any tendency for the support 8 to work away from the shank and catch on inequalities of the ground or other working surface. The support end or tip 13 being initially above the line α , as shown in Figs. 3 and 4, subsequently tends to hub the shoe sole 2 more closely, even, than the rest of the support 8. In order to allow the surface 12 to accommodate itself to the bending action, a slot 14 is provided at the point where the arch support joins the heel.

In the present instance, holes 15 are shown that extend through imbedded washers 16 in the arch support 8 and the heel 5 for the securing nails, or other fastenings.

In Fig. 3, the heel is shown the full depth of the arch support, while, in Fig. 8, the heel is illustrated as being of a depth less than the arch support. This construction is used when the arch support is applied to a used shoe whose heel has not been worn down very much, and it is not desired to remove the entire heel from the shoe.

It will be seen that my improved heel and arch support is flexible and yields under pressure, yet is sufficiently firm and substantial to support the arch of a foot under all conditions.

In some instances, the arch support may be made independent of the heel and will be flexed when applied to the shank of a shoe.

From the foregoing description, it will be seen that the arch support 8 is so formed and located as to accommodate itself to the longitudinal and transverse curvatures of the foot. Being offset from the center sufficiently to lie under the articulation of the scaphoid and the astragalus, it effectively supports this portion of the foot, where the greatest weight is brought to bear. (It is the displacement of the scaphoid which produces the condition known as "fallen arch", so prevalent among heavy

people, and those subjected to excessive foot strains from long periods of standing or the like.) Its main body affords a maximum of resilient cushioning support to the scaphoid bone at the point of greatest curvature and height of the arch, just in front of the heel 5; while at the same time its forward tapering front portion and the location of its end 13 in relation to the ball of the foot permit the transverse (metatarsal) arch to function properly. Supporting the longitudinal arch under its inner aspect (defined by the astragalus, scaphoid, internal cuneiform, and first metatarsal bones), as already mentioned, it affects the transverse arch only by sustaining its inner side in normal position at the rear of the common anchorage of the longitudinal and transverse arches in the first metatarsal bone. Unlike support applied under the mid-portion of the transverse arch (as defined by the middle cuneiform bone and the junctions of the scaphoid and astragalus with the cuboid bone), therefore, it has no distorting tendency of its own: e. g., it does not lift the "keystone" of the transverse arch (so to speak) while leaving its sides or edges unsupported.

When pressure is applied to the tread or bearing surface 12 in walking, the wearer's weight is firmly, evenly, and yieldingly supported from the ground; and the fatigue resulting from immobility of the muscles with relatively rigid or unyielding metal braces is avoided. Being itself universally yielding and resiliently flexible, the device 4 as a whole does not render the shoe shank unyielding, but, on the contrary, permits it to accommodate itself freely to the foot and the ground.

In a word, the device not only supports the scaphoid properly under all conditions and prevents the foot bones generally from assuming abnormal positions such as give rise to the condition known as fallen arch, but also relieves and rectifies such conditions previously existing, by pushing the movable bones into their proper places and keeping them there, so as to aid the muscles and tendons in recovering their normal condition and tone. The exercise permitted the muscles by the yielding character of the device appears to be particularly beneficial in this regard.

Having thus described my invention, I claim:—

1. As an article of manufacture, a one-piece support of resilient rubber, comprising a heel portion and an arch supporting portion extending, when the device is applied to a shoe and by virtue of its own unconstrained configuration, from a point inside the middle of said heel portion forward under the inner aspect of the wearer's foot, with its bearing surface offset sufficiently from the center to lie under and support the

articulation of the astragalus and the scaphoid and substantially flush with the heel and the ball of the shoe, even when off the ground, and with its forward end entirely inside the middle of the shoe sole.

2. As an article of manufacture, a one-piece support of resilient rubber comprising a heel portion and an arch supporting por-

tion extending forward therefrom; said latter portion having its upper surface substantially not below a straight line with that of the heel portion, so that said portion requires downward flexure to accommodate the device to a shoe and is thereby caused to hug the shoe sole. 10

FRANK H. CHASE.
